SPARK PLUG

William Harper, Jr., Port Washington, N. Y., assignor to H. B. Motor Corporation, New York, N. Y., a corporation of New York

Application June 13, 1936, Serial No. 84,991

17 Claims. (Cl. 123—169)

This invention relates to spark plugs, and aims to increase the efficiency and smoothness of operation of internal combustion engines.

The rapidity of the ignition of the fuel mixture contained in an internal combustion engine is one of the factors which affects the power output per unit of fuel and also the smoothness of operation. For most satisfactory operation of the engine, the ignition of the entire fuel charge should be as nearly as possible instantaneous.

I have ascertained that the rate of propagation of flame in an explosive mixture in an internal combustion engine is relatively slow when the engine is operating at less than its maximum power. I attribute this to the fact that, when the throttle is partially closed so that the engine develops less than its maximum power, the fuel charge which is drawn into the engine is diluted to a substantial extent by the burnt gases which remain in the clearance space between the piston and the head of the cylinder at the end of the exhaust stroke. While such unexhausted burnt fuel is small compared to the displacement volume of the piston, it is of substantial volume in comparison with the volume of fuel drawn in when the engine is throttled down. The presence of burnt gases mixed with the incoming fuel appears to have the effect of reducing the speed of propagation of the flame when the charge is ignited from a spark, as is customary. The slowness of the ignition materially reduces the efficiency of the engine.

The spark plug which I have invented produces practically instantaneous ignition, even when the fuel and air mixture in the engine is diluted with burnt gases. Its use thus adds to the fuel efficiency of automobile engines. It has also other advantages which will hereinafter appear from a detailed description of the spark plug embodying my invention, which are shown as illustrative examples in the accompanying drawing in which:

Fig. 1 is an axial section of a unitary spark plug embodying the invention and adapted to be screwed into an opening in a cylinder head;

Fig. 2 is a transverse section on the line 2—2 of Fig. 1;

Fig. 3 is a transverse section on the line 3—3 of Fig. 1, indicating the manner in which burning gases are projected from the spark plug into the cylinder;

Fig. 4 is an axial section of a composite spark plug similar to that shown in Fig. 1, except that it consists of an ordinary spark plug screwed into a special casing;

Fig. 5 is a transverse section on the line 5—5 of Fig. 4;

Fig. 6 is an axial section of a unitary spark plug adapted to be screwed into the wall of a cylinder; and

Fig. 7 is a transverse section on the line 7—7 of Fig. 6.

The spark plug shown in Figs. 1, 2 and 3 includes an insulator 11 of ordinary construction, a metal body 12 of special construction, and two electrodes 10, 21. The insulator 11 is preferably a porcelain insulator with a long skirt such as is used in the Champion 14 mm. spark plug. The body 12, which most desirably consists of a single piece of metal, has a nut portion 15, an externally threaded tubular portion 16 which extends well beyond the inner end of the insulator 11, and a shield portion 17 which substantially closes the inner end of the tubular portion but contains passages hereinafter described. In the form illustrated in Fig. 1, the shield portion 17 provides a hollow projection of reduced diameter projecting from the inner end of the tubular portion 16. The body 12 supports the insulator 11 in the usual manner, a nut 13 being used to secure the insulator to the body. The tubular portion 16 and the shield portion 17 of the body enclose the inner end portion of the insulator 11, and provide a chamber 14. The chamber 14 has a cylindrical portion 18 within the tubular portion 16 of the body, a well 19 of reduced diameter within the shield 17, and a flaring portion 20 connecting the well and the cylindrical portion. The body 12 carries a transverse electrode 21 beyond the inner end of the insulator 11. The electrode 21 cooperates with the central rod electrode 10 to provide a spark gap 22 at the inner end of the cylindrical portion 18 of the chamber 14.

When the body 12 is screwed into the spark plug opening of a cylinder, the threaded portion 16 of the body is in the wall of the cylinder head, while the shield 17 of the body projects inwardly from the cylinder head into the clearance space provided between the cylinder head and the end of the piston. The chamber 14 is placed in communication with the cylinder by passages or bores 23 extending through the side wall of the projecting shield 17 from its outside to the well 19. As seen in Fig. 1, the bores 23 are inclined upwardly at a small angle as they enter the well 19. As seen in Fig. 2, the bores 23 are inclined to radii the body so that they enter the well 19 tangentially.

The operation of this spark plug is as follows: During the compression stroke of the engine, the

fuel mixture, which may be diluted with a certain amount of burnt gas, enters the chamber 14 through the bores 23, displacing burnt gas remaining in the chamber into the upper portion of the 5 chamber surrounding the insulator 11, so that the fuel mixture fills the lower portion of the chamber 14 and surrounds the spark gap 22. From the inclination of the bores, it results that the fuel mixture enters as a swirling body of gas rising 10 from the well 19 into the lower part of the cylindrical portion 18 of the chamber 14. This swirling body of gas displaces the burnt gas in the chamber without substantial intermixiture therewith. The spark gap 22 is located substantially 15 on the axis of the swirling body of fuel mixture. This places the fuel mixture in the best condition for quick ignition from a spark in the gap, since the molecules of fuel in the swirling body are directly exposed to a spark at the gap, even though they are separated by molecules of 20 burnt gas between them. Furthermore, as the bores 23 are not directed towards the spark gap and the spark gap is located axially in the swirling mixture, there is no current of gas across the 25 spark gap which, by its blowing action, would interfere with the effectiveness of the spark. It follows that when a spark is produced at the gap 22, the fuel mixture in the lower portion of the chamber 14 is instantly ignited. The expanding burning gas passes out through the bores 23 as jets of flame extending well into the body 30 of mixture in the clearance space between the cylinder head and the piston, so that this body is instantly ignited by direct contact with the 35 flame, even though the presence of molecules of burnt gas between the fuel molecules tends to reduce the rate of flame propagation in the mixture.

The insulator 11 is protected from radiant heat 40 from the burning mixture in the cylinder by the shield 17. This result is attained by so directing the passages 23 that no straight line which can be drawn through them will intersect the insulator.

The spark plug shown in Figs. 1 and 2 is provided 45 with means for regulating and observing the width of the spark gap 22. The transverse electrode 21 has a drive fit in the body 12, so that the distance of its end from the rod electrode 10 may be varied by driving it in or out in this 50 hole. In order that the adjustment may be observed after the spark plug has been assembled, a transverse bore 24 is provided in the threaded portion 16 of the body. As seen in Fig. 2, this bore is not quite diametrical, but has its axis 55 nearly on a tangent to the rod electrode 10 so as to provide a small window through which the width of the spark gap 22 may be observed before the spark plug is screwed into the cylinder head. After the spark plug has been screwed in, the 60 ends of the bore 24 are closed by the wall of the cylinder, so that the presence of this bore does not interfere with the operation which has been described.

Figs. 4 and 5 show an ignition device similar 65 to that shown in Fig. 1, except that the one-piece body 12 is replaced by a composite body consisting of the body 26 of an ordinary spark plug 27 and a special casing 25 into which the spark plug 26 is screwed. The casing 25 has a nut portion 15' and a tubular portion 16' which is threaded internally for reception of the spark plug body 26, and also threaded externally like the tubular portion of the ignition device shown in 70 Fig. 1. The shield 17' at the end of the tubular

portion 16' and the well and bores contained therein are similar to corresponding parts in Fig. 1. The casing 25 carries no electrode, since a spark gap 22' near the lower end of the cylindrical portion 18' of the chamber 14' is provided by the two conventional electrodes 10', 21' of the spark plug 27.

It is thus apparent that the casing 25 provides an attachment which may be screwed upon an ordinary spark plug to provide an ignition device 10 similar to that shown in Fig. 1.

The spark plug shown in Figs. 6 and 7 is designed to be placed in an opening in a cylinder wall rather than in a cylinder head. The tubular portion 16' of its body 12' is closed at its end by 15 a shield 17' having the form of a transverse wall with concave inner and outer surfaces. At the center of the inner surface of this wall is an electrode 21' which cooperates with the central rod electrode 10' to provide a spark gap 22' near 20 the lower end of the chamber 14'. Passages or bores 23' extend through the wall 17'. The bores 23' are inclined outwardly from the axis of the device as they pass inwardly through the shield 17'. At the inner end of each bore is a deflecting 25 surface 28 which directs gas entering through the bores toward the axis of the device above the spark gap 22'. In this case, the body of fuel mixture entering through the bores tends to swirl in planes parallel to the axis of the spark plug 30 and, as before, the entering gas is directed so as not to cause a current of gas across the spark gap.

The flame directed outwardly through the bores 35 23', after the gas in the chamber 14' has been ignited, is directed in the general direction of the axis of the device, so that the flame passes across the fuel mixture contained in the clearance space between the cylinder head and the piston from a point on the circumference of this space. 40

The width of the spark gap 22' may be adjusted by placing shims between the insulator 11' and the shoulder of the body 12' on which the insulator rests. The adjustment may be observed through a diametrical window bore 24' in 45 the tubular portion 16' of the body.

In this specification and in the claims which follow, the words "inner end" have been used in connection with various parts of the spark plugs to indicate the end which is directed into the 50 cylinder when the spark plug is in use, that is to say, the lower ends of the parts of the spark plugs as they appear in Figs. 1, 4 and 6.

While the drawing shows three of the passages 55 23, the number of passages may be varied as desired without departing from my invention, and it is practical, although less desirable, to use only one such passage. Consequently, in the claims which follow the number of passages is not specified and the word "passages" where used in the claims should be understood to include the use of only one passage except where a "plurality" of passages is expressly specified.

What I claim is:

1. A spark plug comprising an insulator, a metal body supporting the insulator and having an externally threaded tubular portion extending beyond the inner end of the insulator, a shield closing the inner end of said tubular portion and providing a hollow projection of less diameter than said tubular portion, and electrodes positioned to provide a spark gap within the tubular portion of the body near its inner end, said hollow projection containing restricted passages 75

- through its side walls directed towards points spaced from the spark gap.
2. A spark plug comprising an insulator, a metal body supporting the insulator and forming a casing providing an enclosed chamber surrounding the inner end of the insulator and having a cylindrical portion and a well of reduced diameter, the casing containing restricted passages entering said well and inclined towards the peripheral portion of the lower end of the cylindrical portion of the chamber, and electrodes positioned to provide a spark gap located in the cylindrical portion of the chamber close to its inner end.
3. A spark plug comprising an insulator, a metal body supporting the insulator and forming a casing providing an enclosed chamber surrounding the inner end of the insulator and having a cylindrical portion and a well of reduced diameter, said casing containing a plurality of restricted passages entering the well of the chamber tangentially, and electrodes positioned to provide a spark gap located close to the inner end of the cylindrical portion of the chamber.
4. A spark plug comprising an insulator, a metal body supporting the insulator and forming a casing providing an enclosed chamber surrounding the inner end of the insulator and having a cylindrical portion and a well of reduced diameter, said casing containing a plurality of restricted passages, each having a length greater than its width and entering the well of the chamber tangentially and inclined toward the inner end of the cylindrical portion of the chamber, and electrodes positioned to provide a spark gap located close to the inner end of the cylindrical portion of the chamber and near the axis of the chamber so that it is not in line with said tangential passages.
5. The method of igniting a fuel mixture in an internal combustion engine, which consists in causing a small part of the mixture to swirl about an axis, producing a spark within the swirling body of gas at an intermediate point of its axis to ignite this part of the mixture, and projecting jets of flame produced by the ignition in this part of the mixture into the main body of the mixture.
6. A spark plug comprising an insulator, a metal body supporting the insulator and forming a casing providing an enclosed chamber surrounding the inner end of the insulator, electrodes positioned to provide a spark gap near the inner end of the chamber, said casing containing a restricted passage so directed as to cause gas entering therethrough to swirl in the inner end portion of the chamber about the spark gap as a center and so proportioned that a straight line drawn through it cannot intersect the insulator.
7. A spark plug comprising an insulator, a metal body supporting the insulator and providing an enclosed chamber surrounding the inner end of the insulator, electrodes positioned to provide a spark gap substantially on the axis of the chamber, said casing containing a plurality of restricted passages each having a length greater than its width and entering the chamber tangentially to create therein a body of gas swirling about the spark gap as a center.
8. The method of igniting a compressed fuel mixture in an internal combustion engine which comprises so moving a small part of the mixture as to create a zone of reduced pressure therein, producing a spark in this zone of reduced pressure to ignite this part of the mixture, and projecting jets of flame produced by the ignition of this part of the mixture into the main body of the mixture.
9. A spark plug comprising an insulator, a metal body supporting the insulator and forming a casing providing an enclosed chamber surrounding the inner end of the insulator, and electrodes positioned to provide a spark gap in the chamber, said casing containing restricted passages entering the chamber tangentially below the spark gap and all inclined in the same direction to cause the entering gas to swirl in the chamber.
10. A spark plug comprising electrodes, an insulator, and a metal body supporting the insulator and the electrodes and forming a casing providing an enclosed chamber surrounding the inner end of the insulator and containing passages all of which enter the chamber tangentially at points spaced from its axis.
11. A spark plug comprising an insulator, a metal body supporting the insulator and forming a casing providing an enclosed chamber surrounding the inner end of the insulator, and electrodes positioned to provide a spark gap in the chamber, said casing containing restricted passages so inclined and arranged as to direct all gas entering the chamber against the outer circumferential wall of the chamber immediately upon its entrance and before it strikes the insulator or the spark gap.
12. A spark plug comprising an insulator, a metal body supporting the insulator and having an externally-threaded tubular portion extending beyond the inner end of the insulator, a shield closing the inner end of said tubular portion, and electrodes positioned to provide a spark gap near the inner end of the chamber enclosed by the body and shield, said shield containing restricted passages, all of which are so inclined that the axis of no one of them intersects the insulator and the axis of no one of them passes through the spark gap.
13. A spark plug comprising an insulator, a metal body supporting the insulator and forming an enclosed casing surrounding the inner end of the insulator, and electrodes positioned to provide a spark gap in the chamber, said casing containing a plurality of restricted passages so inclined that their axes do not intersect each other and no one of them intersects either the insulator or the spark gap.
14. In a spark plug, the combination of an insulator and a metal body supporting the insulator and forming a casing providing an enclosed chamber surrounding the inner end of the insulator, said casing containing restricted passages so inclined and arranged as to direct all gas entering the chamber against the outer circumferential wall of the chamber immediately upon its entrance and before it strikes the insulator.
15. In a spark plug, the combination of an insulator, a metal body supporting the insulator and having an externally-threaded tubular portion extending beyond the inner end of the insulator, and a shield closing the inner end of said tubular portion and containing restricted passages having lengths at least one-half as great as their widths and all so inclined that a straight line drawn through any one of them cannot intersect the insulator.
16. A spark plug comprising electrodes providing a spark gap, an insulator, and a metal body forming a casing providing an enclosed chamber surrounding the inner end of the insu-

lator and the spark gap and containing gas entrance passages so positioned that a straight line drawn through any one of them cannot intersect the insulator and so inclined as to cause the entering gas to swirl in the chamber.

17. A spark plug comprising an insulator, a metal body supporting the insulator and forming a casing providing an enclosed chamber sur-

rounding the inner end of the insulator and containing passages inclined so as to cause the entering gas to swirl about the axis of the chamber, and a pair of electrodes positioned to provide a spark gap in the chamber spaced from its inner end and substantially on its axis.
